UNITED STATES PATENT OFFICE.

HORACE HOLDEN, OF EAST ORANGE, NEW JERSEY.

SOUNDING-LEAD.

SPECIFICATION forming part of Letters Patent No. 398,396, dated February 26, 1889.

Application filed July 7, 1888. Serial No. 279,285. (No model.)

To all whom it may concern:

Be it known that I, HORACE HOLDEN, of East Orange, Essex county, State of New Jersey, have invented a new and Improved Sounding-Lead, of which the following is a specification.

This invention relates to a sounding-lead for mariners' use, which is so constructed that the ground taken up by the arming will be protected while being drawn upward through the water. Thus the ground will not be apt to be partly or entirely washed away before it reaches the surface.

The invention consists in the various features of improvement more fully pointed out in the claims.

In the accompanying drawings, Figure 1 is a side view of my improved sounding-lead, showing the sleeve down. Fig. 2 is a vertical longitudinal central section of Fig. 1. Fig. 3 is a similar section as Fig. 2, but with the sleeve up.

The letter *a* represents a sounding-lead of conical or other suitable shape, and having a cavity in its bottom to receive the arming *b*, as usual. Around the lead *a* there is placed a sleeve, *d*, open at top and bottom, and having preferably a flange, *e*, at its upper end.

The sleeve *d* is free to slide up and down on lead *a*. Its upward motion is limited by screws or stops *f*, projecting laterally from the lead *a*. The downward motion of the sleeve *d* is limited by the flange *e*, when closely embracing the conical body of the lead *a*, or by a laterally-projecting flange, *g*, at the bottom of the lead.

The operation of the device is as follows: The lead, being dropped, will pass swiftly

through the water so that the resistance of the water acting against the lower edge of the sleeve *d* will force the same upward until its flange *e* strikes against the stops *f*. The sleeve is of such a length only that in this position the cavity, with its arming *b* will be exposed, Fig. 3, so that as the lead strikes the ground 45 the latter can come in contact with and adhere to the arming. The lead being next raised, the gravity of the sleeve, together with the pressure of the water on its upper edge, will cause it to drop down into the position 50 shown in Fig. 2, so as to project beneath the base of the lead. Thus the arming and ground will be protected against all currents, and the ground may thus be raised to the surface without being washed away. 55

What I claim is—

1. The combination of a sounding-lead having a cavity in its base for the reception of the arming with a sliding sleeve surrounding the lead and adapted to be projected beyond its 60 base, substantially as specified.

2. The combination of a conical sounding-lead with a sleeve embracing said lead and having flange *e*, and with the stop *f*, substantially as specified. 65

3. The combination of a sounding-lead, *a*, with a surrounding sleeve, *d*, having flange *e*, and with the stop *f* above sleeve *d*, and with the laterally-projecting flange *g* at the lower end of the lead *a*, substantially as specified. 70

HORACE HOLDEN.
